2,329,120

LATCH MECHANISM

Theodore N. King, Jackson, Mich., assignor to
Hancock Manufacturing Company, Jackson,
Mich., a corporation of Michigan

Application March 27, 1941, Serial No. 385,513

5 Claims. (Cl. 292—4)

The present invention relates to latching devices, and in particular provides an improved latch construction of the rotary bolt type.

The principal objects of the present invention are to provide a latch construction of the above general type, which is simple in construction, economical of manufacture, and which is reliable and efficient in operation; to provide such a construction embodying an improved arrangement for holding an associated door in the partially closed or safety position; to provide such an arrangement wherein the door is provided with a bolt which releasably engages a keeper carried on the associated pillar, and is also provided with a supplemental or safety bolt which cooperates with the pillar to hold the door in a partially closed or safety position; to provide such a structure wherein the bolt is provided with holding means which are retractable, but which normally prevent the main bolt from being released from the keeper, and wherein the means for retracting the holding means is also effective to retract the safety bolt, so as to permit an opening movement of the door; and to provide such a structure wherein the supplemental bolt is retractable by and during a closing movement of the door, but positively prevents an opening movement of the door unless retracted, as aforesaid.

With the above, as well as other objects in view, which appear in the following description and in the appended claims, a preferred but illustrative embodiment of the invention is shown in the accompanying drawings, throughout the several views of which corresponding reference characters are used to designate corresponding parts and in which:

Figure 1 is an interior view of a rear vehicle door equipped with the present latch;

Fig. 2 is an enlarged view of the latch and its keeper, showing the parts in the same relation as in Fig. 1;

Fig. 3 is a detail view, taken along the line 3—3 of Fig. 2;

Fig. 4 is a view corresponding to Fig. 2, but showing the parts in the positions occupied when the inside door handle is operated to open the door;

Fig. 5 is a view in section, taken along the line 5—5 of Fig. 2;

Fig. 6 is a view in section, taken along the line 6—6 of Fig. 2; and

Fig. 7 is a view in section, taken along the line 7—7 of Fig. 2.

It will be appreciated from a complete under-

standing of the present invention that in the broader aspects the improvements thereof may be applied to a variety of uses other than the latching of automobile doors, and that such improvements may be embodied in forms which differ from the specific forms herein disclosed. By way of illustration but not of limitation, the present improvements are herein disclosed as applied to the latching of the rear door of an automobile.

Referring to the drawings, the illustrative rear door 10 is hinged, by means not shown, along its front edge to the pillar 12 of the associated vehicle body. The rear edge of the door is provided with a cut-away portion 14 to accommodate the rear wheel housing of the associated body, and this cut-away portion extends upwardly to a point relatively close to the window opening 16 of the door 10. The latch 18 is received within the body of the door in the vertical space between the window opening and the cut-away portion 14.

Except in respects hereinafter noted, the latch 18 follows the construction of Patent No. 2,195,179, granted March 26, 1940, and comprises generally a rotary bolt 22, having a series of equi-angularly spaced, generally radially extending keeper-engaging teeth 24 and a corresponding series of cam engaging teeth 26. The bolt 22 is pivotally supported upon the flange of the case plate by means of a pivot pin 28, one end whereof is journaled in a housing 30, which encloses the lower portion of that part of the bolt 22 which projects outwardly of the rail 10a of the door 10, and the inner end whereof is pivotally supported upon a deck 32, which is secured to the flange 34 of the latch plate, but in inwardly spaced relation thereto. The door rail 10a and the flange 34 of the case plate are provided with registering openings through which the body of the bolt 22 and the housing 30 are projected, and it will be observed that the keeper engaging teeth 24 are positioned externally of the door rail 10a, whereas the cam engaging teeth 26 are positioned within the door, in the space between the case plate flange 34 and the deck 32.

In order to prevent rotation of the bolt 22 in a door opening direction, the bolt is provided with a series, three being shown, of cams designated collectively as 36. The cams 36 are pivotally supported between the flange 34 and the deck 32 by means of a pin 38, and the upper end portions 36a of the cams 36 are deflected to accommodate the correspondingly angled portion

of the rail 10a. The cams 36 are continuously biased to the normal positions shown in Fig. 5, by means of usual springs 40, one whereof is provided for each cam. In accordance with the arrangement disclosed in the above-numbered patent, the cams 36 are, relative to each other, of progressively increasing size, and the shortest cam is provided with a laterally offset foot 42 for cooperation with the nose 44 of the hereinafter described retracting lever 46. In addition, the just-mentioned shortest cam is provided with a second foot 48, which overlies the backs of the other cams, so that a retracting movement of such shortest cam is accompanied by corresponding retracting movements of the other cams.

The rail 10a of the door is provided with an abutment 50, which extends outwardly therefrom towards the pillar 12, and which is positioned above the outer or keeper engaging teeth 24 of the bolt. The keeper 52, which is herein illustrated is being formed from a stamping, is secured to the portion 13 of the body which opposes the door rail 10a and, when the door is closed, extends into the space between the abutment 50 and the bolt 22. The keeper 52 is provided with an upper surface 54, which slopes upwardly in the direction of door closing movement, and the cooperating under surface of the abutment 50 is correspondingly angled. The lower side of the keeper 52 is of toothlike form, having a surface 56 for initial engagement by a tooth of the bolt during a closing movement of the door, and having an upwardly angled holding surface which is engaged by a tooth 24 of the bolt when the door is fully closed.

In accordance with the present arrangement, the keeper 52 and the bolt 22 cooperate to hold the door in the fully closed position, as will be appreciated, and the means for holding the door in a partially closed or safety position comprises a supplemental bolt 60, which is carried by the door 10 and cooperates with an abutment or keeper 62, which is carried by the previously mentioned portion 13 of the body. In its normal position, the supplemental bolt 60 projects outwardly from the door rail 10a in the cut-away portion 14 thereof. The supplemental bolt 60 is pivotally mounted by means of a pin 64 in a channel-shaped stamping 66, which in turn is pivotally supported on a pin 68. The pin 68 is supported by the portion 70 of the case plate flange, which portion is angled to conform to the cut-away portion 14 of the door. The portion 70 is provided with a slotlike opening having the side walls 72 and 74, between which the stamping 66 is received when the supplemental bolt 60 is in its active position, and the rail 10a of the door is provided with an opening 76 through which the bolt 60 projects. The supplemental bolt 60 is normally urged to the position shown in Fig. 7, by means of a torsion spring 78, which is coiled about the pin 64, but, as will be appreciated, may be swung counterclockwise against the force of the spring 78, so as to enable the bolt 60 to pass over the abutment 62 during a closing movement of the door.

The means for retracting the cams 36 from holding engagement with the bolt 22, and for also rocking the stamping 66 about the pivot pin 68, so as to retract the supplemental bolt 60 into the door, comprises the previously mentioned retracting lever 46. Lever 46 is pivotally mounted between the base 80 of the case plate and a usual deck 82, which is carried thereby but spaced

therefrom by means of a pivot pin 84, and is provided with the previously mentioned cam engaging nose 44, a nose 86 and an armlike extension 88. The nose 86 is disposed in the path of movement of a laterally turned foot 90 formed on a supplemental lever 92, which is also pivotally mounted upon the pin 84 and is normally urged to the position shown in Fig. 2 by means of a usual spring 94. The arm 88 is provided with a pin 96, which is received in an elongated slot 98, provided in the link 100 which, as will be understood, extends to the usual inside handle 103. The just-mentioned pin and slot provide, as will be understood, a lost motion connection between the retracting lever 46 and the link 100.

The supplemental lever 92 is disposed to be operated by the usual rollback 102, which is provided with a squared spindle 104. The spindle 104, in turn, is connected to the outside door handle 106, and it will be understood that, if desired, the rollback 102 may be of the scissorlike form described and claimed in Moore Patent No. 1,395,893, which is assigned to the assignee of the present application. The retracting lever 46 and the previously mentioned stamping 66, associated with the supplemental bolt 60, are connected together by a rod 110, one turned end 112 whereof is hooked through the end of the lever 46, and the other turned end 114 whereof is hooked through the stamping 66. With this relation, it will be appreciated that each clockwise movement of the lever 46, which occurs in response to an operation of either the inside or outside handle, as hereinafter described, rocks the stamping 66 about the pivot pin 68 and elevates the supplemental bolt 60 out of range of the cooperating abutment 62.

In accordance with the disclosure of the pending application of Rollo Marple, Serial No. 235,982, filed October 20, 1938, and assigned to the assignee hereof, the present arrangement employs a locking roller 120, which is carried at the end of a link 122 and one end whereof rides in an elongated slot 124 in the plate 80. The other end of the link 122 is connected, through a bell crank 126, to a locking push button 128, which normally projects upwardly through the garnish molding of the door 10. A depressing movement of the push button 128 causes the roller 120 to advance downwardly and to the right, as viewed in Figs. 2 and 4, and brings the body of the roller 120 into blocking relation to the arcuate portion 130 of the retracting lever 46. With the roller 120 in the just-mentioned position, clockwise or retracting movement of the lever 46 is prevented, and both the inside and outside handles are consequently rendered ineffective to release the bolt. In order to enable a closing movement of the door to reset the locking roller 120 to the unlocked position of Figs. 2 and 4, the kickoff lever 132 is provided. The lever 132 is pivoted on the previously mentioned pin 84 between the retracting lever 46 and the deck 82. One end 134 of the lever 132 lies beneath the previously mentioned foot 42, associated with the cams 36, and the other end 136 thereof lies below and in camming relation to the locking roller 120. As described below, a closing movement of the door swings the cams 36, and consequently rocks the lever 132 in a clockwise direction. This action is without effect if the locking roller 120 is in the normal position, but if such roller is in the locking position, this movement of the lever 132 cams the roller 120 to the unlocked position.

It is noted that the lever 92 lies immediately adjacent the plate 80, and the lever 132 lies immediately adjacent to the deck 82, the lever 46 being positioned therebetween, as aforesaid. The lower end of the arm 88 of the lever 46 is offset so as to clear the flange 90, so that the lever 46 may be operated by the inside handle without altering the position of the lever 92.

Considering now the operation of the system as a whole, the parts are shown in Figs. 2, 3, 10, 6 and 7 in the normal or fully closed position thereof, with the locking button 128 in the unlocked position, so that the locking roller 120 does not interfere with retracting movement of the retracting lever 46. If the outside handle 106 is rocked in a counterclockwise direction, as viewed in Figs. 1 and 2, rollback 102 is correspondingly rocked. The engagement between the rollback 102 and the flange 90 of the lever 92 transmits the motion of the rollback to the lever 92. In turn, the engagement between the flange 90 and the nose 86 of the retracting lever 46 causes the latter to swing in a clockwise direction. During such movement, the pin 96 rides in the slot 98, associated with the remote link 100, so that the motion of the lever 46 is not communicated to the inside handle. A similar rocking movement of the lever 46 may be accomplished by swinging the inside handle 103 in an opening direction which, through the arm 88, rocks the lever 46 in a clockwise direction. Due to the offset in the arm 88, this motion is not communicated to the lever 92, which remains effective to hold the rollback 102 and the outside handle 106 in the normal position.

The clockwise movement of the lever 46, produced by operating either the inside or outside handle, enables the nose 44 thereof to bear against the foot 42, associated with the cams 36, and swing the latter from the full line position of Fig. 5 to the dotted line position thereof. In this latter position, the cams 36 do not interfere with free rotation of the bolt 22 in a counterclockwise or door opening direction. The movement of the lever 46 also elevates the connecting rod 110, which, through the stamping 66, elevates the supplemental bolt 60 out of range of its cooperating abutment 62. Under the conditions stated, accordingly, the door may freely be opened, and as soon as the supplemental bolt 60 has passed beyond the range of the abutment 62, the inside or the outside handle, as the case may be, may be released, thereby restoring the parts to the positions shown in Figs. 1, 2, 5, 6 and 7. The release of the outside handle enables the spring 94, associated with the lever 92, to restore this lever and rollback 102 to the positions shown in Fig. 2. The usual return spring (not shown) associated with the inside handle 103 may be relied upon to restore this handle and the link 100 to the positions shown in Fig. 2. Also, as soon as the bolt passes out of range of the cams, the springs 40 associated therewith are effective to restore these cams to the full line position, which action, through the foot 42, restores the lever 46 to the position shown in Fig. 2. The latter action causes the supplemental bolt 60 to be projected to the position shown in Fig. 7.

If the door is now swung towards the closed position, the back of the supplemental bolt 60 engages the sloping face of the abutment 62, and this action rocks the bolt 60 in a counterclockwise direction sufficiently to permit the continued door closing movement. When the door reaches

the usual partially closed or safety position, the bolt 60 passes beyond the end of the abutment 62, whereupon the spring 78, associated therewith, is enabled to swing the bolt 60 to the active position in which it is effective to prevent a re-opening movement of the door unless either the outside or the inside handle is operated, as before, to retract the bolt 60.

As the door closing movement continues, the leading face of that one of the teeth 24 of the bolt 22 which is in the uppermost position engages the face 56 of the keeper 52. The continued door closing movement enables the keeper 52 to rock the bolt 22 in a clockwise direction, bringing the next successive tooth 24 into holding engagement with the face 58 of the keeper. The clockwise force applied to the bolt 22 by the keeper face 56 enables the corresponding inner tooth 26 of the bolt to bear against the back of the cams 36 and swing them in a counterclockwise direction sufficiently far to enable such tooth to pass the cams. As soon as such tooth has passed the cams, the springs 40 are effective to restore the cams to the locking position, as shown in Fig. 5.

The just-mentioned rocking movement of the cams 36 causes a corresponding up and down movement of the foot 42, associated therewith, and this action is enabled to rock the kickoff lever 132 in a counterclockwise direction. This movement is an idle movement unless, as aforesaid, the locking roller 120 is in locking position. In the latter event, however, such movement of the kickoff lever 132 cams the roller 120 back to the normal or unlocked position.

Although only a single specific embodiment of the invention has been described in detail, it will be appreciated that various modifications in the form, number and arrangement of parts may be made without departing from the spirit and scope of the invention.

What is claimed is:

1. In a latch for cooperation between first and second members, the combination of a first bolt carried by one of the members and cooperable between the members to hold them in a closed position, a second bolt carried by one of the members and cooperable between the members to hold them in a partially closed position, a movable support for at least one of said bolts, and operating means including means operable to effect a movement of said support and render said one bolt ineffective to hold the members, said operating means further including means cooperable with the other bolt to render it ineffective to hold the members, said one bolt being movable relative to its support so as to enable a closing movement of said members to be effected without causing a movement of said support.

2. In a latch for cooperation between first and second members, the combination of a first bolt carried by one of the members and releasably engageable with a corresponding keeper surface carried by the other member to hold said members in a closed position, a second bolt carried by one of the members and releasably engageable with a corresponding keeper surface carried by the other member to hold said members in a partially closed position, a movable support for one of said bolts, and operating means including means operable to move said support and render said one bolt ineffective to hold the members, said operating means further including means cooperable with the other bolt to render it ineffective to hold the members, said one bolt being

movable relative to its support so as to enable it to yieldingly pass over the corresponding keeper surface during the closing movement of the members.

3. In a latch for cooperation between first and second members, the combination of a first bolt carried by one of the members and releasably engageable with a corresponding keeper surface carried by the other member to hold said members in a closed position, a supplemental bolt carried by one of the members and releasably engageable with a corresponding keeper surface carried by the other member to hold the members in a partially closed position, a movable support for said supplemental bolt, and operating means including means operable to render the first bolt ineffective to so hold the members and to move said support whereby to render the supplemental bolt ineffective to so hold the members, said supplemental bolt being movable relative to its support so as to enable it to yieldingly pass over the corresponding keeper surface during a closing movement of the members.

4. In a latch for cooperation between first and second members, the combination of a bolt carried by one of the members and releasably engageable with a keeper carried by the other member to hold said members in a closed position, holding means engageable with said bolt to urge the same into engagement with said keeper, a supplemental bolt carried by one of the members and releasably engageable with means carried by

the other member and defining a second keeper surface to hold the members in a partially closed position, operating means common to said supplemental bolt and to said holding means for retracting the same so as to permit an opening movement of said members, said first-mentioned bolt being cooperable with said keeper during a closing movement of the members to retract said holding means out of holding relation thereto, and said supplemental bolt being retractable by said second keeper surface during a said closing movement.

5. In a latch for cooperation between first and second members, the combination of a bolt carried by one of the members and releasably engageable with a keeper carried by the other member to hold said members in a closed position, a retractable cam for holding said bolt in engagement with said keeper, a supplemental bolt carried by said one member and releasably engageable with means carried by the other member and defining a second keeper surface to hold said members in a partially closed position, and operating means common to said supplemental bolt and to said cam for releasing the same so as to permit an opening movement of said members, said supplemental bolt being bodily retractable by said last-mentioned means and also being swingably retractable as an incident to a closing movement of said members.

THEODORE N. KING.
